UNITED STATES PATENT OFFICE.

JAMES B. SELLS, OF LONDON, KENTUCKY.

CHURN.

1,111,187.

Specification of Letters Patent. Patented Sept. 22, 1914.

Application filed December 5, 1913. Serial No. 804,835.

To all whom it may concern:

Be it known that I, JAMES B. SELLS, a citizen of the United States of America, residing at London, in the county of Laurel 5 and State of Kentucky, have invented certain new and useful Improvements in Churns, of which the following is a specification.

This invention relates to certain improvements in reciprocatory churns of that type in which a dasher is actuated to have a vertical reciprocatory movement in a churn body, and in a churn made in accord with my invention there is present a vertical 15 standard which carries means for connecting the churn body with the standard, there also being present and attached to the standard guides for a reciprocatory bar which bar is maintained in parallel relation with the 20 standard. The standard is also provided with means for supporting driving mechanism for the reciprocatory bar which comprises a fly wheel and pitman rod which are actuated by gears maintained on the opposite 25 side of the support from the fly wheel.

In a churn constructed as shown in the accompanying drawings the reciprocatory bar is provided with means for associating therewith a mixer or vessel, which is agitated when the dasher rod of the churn body is reciprocated, and the construction of the 30 parts that are associated with the reciprocatory bar are such that the member to which the upper end of the dasher rod is attached also serves as a support for a vessel 35 or mixer.

The preferred construction of the driving mechanism is such that an oscillatory lever when actuated will effect by means of alternating pawls which contact with the teeth of the main gear wheel a continuous rotation of said gear wheel.

In the accompanying drawings which illustrate a preferred form of my invention, 45 Figure 1 is a front elevation certain parts being shown in section. Fig. 2 is a side elevation. Fig. 3 is a plan view of means for connecting the dasher rod with a reciprocatory bar, such part also serving as a support for a vessel of the mixer type. Fig. 4 is a detail plan view of the baffle for the 50 mixer or vessel, which is carried by the reciprocating bar, and Fig. 5 is a detail view of the means for connecting the churn body 55 to the standard by means of one of the guides for the reciprocatory bar.

The base 1, has bolted thereto a spider-frame 2 which carries a tubular metallic standard 3 to which are secured guides 4 and 5 and parts 6 and 7 which carry journals for a gear wheel 8, and for a pinion 9 and fly wheel 10. The guides 4 and 5 for a reciprocatory bar 11 have anti-friction rollers 12 and 13 which are arranged to be disposed at right angles to engage opposite 60 sides of the reciprocating bar 11, said rollers being arranged in pairs and being preferably concave. The reciprocatory bar is connected to the fly wheel 10, which is suitably counterbalanced by a weight, by a pitman rod 14 which is attached to the reciprocatory bar 11 between the guides therefor and the particular arrangement of the rollers will prevent the bar 11 binding when the driving mechanism is actuated, which is a desirable feature as the bar 11 is not only intended and adapted to actuate the dasher rod 15, but also carries a vessel or mixer 16. 65

The churn body 17 which rests upon the base 1 is maintained in position by a clamp 18 which is secured to the guide 4 and as the jaws of the clamps are resilient to provide for engagement with churn bodies of different diameters, an adjusting screw having a wing-nut is present to draw the jaws one toward the other and the guide 4 is also adjustably connected to the standard 3. The reciprocatory bar 11 between the guides and above the point of connection of the pitman 14 to the bar carries a member or 70 support 19, which is made up to be adjustably secured to the bar and has beyond its point of attachment therewith a platform 20 that is adapted to provide a rest for the lower end of a vessel 16, and the part 19 beyond the platform is shaped to provide 75 one side of a duplex clamp for the dasher rod 15, the movable member of the clamp is of similar construction and has actuating 80 means consisting of a cam-lever 21 for forcing the movable jaw against the dasher rod. The dasher rod may be held between either 85 of the recessed portions of the clamp as may be required by the diameter of the churn body and to position the parts in alinement 90 the guide 4 may be raised or lowered on the standard to suit the side of the churn body to center the same relative to either recess in the clamp with which the dasher rod 95 engages.

The vessel 16 is provided interiorly with baffles 22 which are connected by a rod 23

which bears against the bottom and the top of the vessel, which top is held in place by an arm or member 24 attached to the reciprocatory bar 11.

5 In practice the cream is placed in the churn body and the churning proceeds in the usual manner when desired, but the preferred practice is to divide the cream placing the major portion in the churn body and 10 a part in the mixer or vessel 16 so that the cream in the vessel will be agitated and aerated after which it is added to the cream in the churn body, and in order that the cream in the vessel 16 may be readily transferred to the churn body 17 the dasher rod 15 may be hollow, its upper end being connected to a stop-cock 25 attached to the vessel 16 so that when the plug of the stop-cock is turned the contents of the vessel 16 20 will be transferred to the churn body through the hollow dasher-rod.

The receptacle 16 when desired may be 25 used independent of the churn body for renovating, merging, or washing butter when deteriorated with milk or cream, or with water when the butter contains an excess of salt. The vessel 16 in practice may be used not only for renovating or merging butter by agitating the butter in the presence of 30 milk or cream, but the vessel may also be used to primarily agitate and aerate cream to prepare the same for being churned in the churn body 17, and the cream may be added to that in the main churn body while the 35 dasher thereof is being actuated.

The actuating mechanism for the gear wheels 8 and 9, preferably consists of a lever 26 one end thereof being constructed to engage with the journal or shaft of the gear 40 8, and the lever carries a pawl 27 which on the downward movement of the lever will positively engage with the teeth of the gear 8. The journal or shaft of the pinion 9 has mounted thereon an arm 28 the outer end 45 thereof having a part of a knuckle joint 29 with which engages a coöperating member of the knuckle joint a part of a pawl for engagement with the opposite side of the gear wheel 8, such pawl 30 being connected 50 to the lever 26 by a link 31. The link 31 is attached to the pawl 30 near the knuckle joint and is attached to the lever 26 between the pawl 27 and its fulcrum upon the shaft of the gear 8. When the lever 26 is oscillated the pawls will alternately engage to drive the gear 8 and rotary movement will be imparted to the pinion to reciprocate the bar 11 with which the vessel 16 and the dasher rod 15 are associated.

60 I do not wish to be limited to the precise

construction of the parts herein shown as they may be varied within the scope of my claims without departing from my invention, as various changes may be made in the instrumentalities used for connecting the 65 parts which may differ as to construction but not as to function.

I claim:

1. In a churn, a support for a reciprocatory rod, a reciprocatory rod, means for associating a churn dash with the reciprocatory rod such means also comprising a support for a mixer, and a mixer maintained by the support.

2. In a churn, a vertical support, a reciprocatory bar associated with the support and with driving means therefor, guides for the reciprocatory bar attached to the support above and below the driving means for the reciprocatory bar, means attached to the support for associating a churn-body therewith, a dasher rod, means for connecting the dasher rod for the churn-body with the reciprocatory bar comprising a member having between the reciprocatory bar and the point of attachment with the dasher rod a support for a vessel, a vessel which is adapted to be maintained by the support and means also attached to the reciprocatory bar for holding the vessel upon its support.

3. In a churn, a vertical standard, means attached to the standard for guiding a reciprocatory bar, a reciprocatory bar, means for reciprocating the bar carried by the standard and operatively connected to the reciprocatory bar, anti-friction rollers attached to the guides and maintained by the different guides at right angles one to the other, a member attached to the reciprocatory bar for connecting the bar to a dasher-rod such 100 member having a part which serves as a support for a vessel and means also attached to the reciprocatory bar for maintaining a vessel upon the support.

4. In a churn, a reciprocatory bar, a member having at one end means for attaching said member with the bar, a clamp on the opposite end of the member for attaching a dasher rod to said member, an intermediate located means for supporting a vessel upon the member and means carried by the bar for engagement with the upper portion of a vessel to retain a vessel in fixed engagement with the reciprocatory bar and the support for the vessel.

JAMES B. SELLS.
